UNITED STATES PATENT OFFICE.

SVANTE ROBERT WILLIAM MATTSSON BAGER, OF MILWAUKEE, WISCONSIN, ASSIGNOR
TO BUCYRUS COMPANY, OF SOUTH MILWAUKEE, WISCONSIN, A CORPORATION OF
WISCONSIN.

DRAG-LINE EXCAVATOR.

1,105,480.

Specification of Letters Patent. Patented July 28, 1914.

Application filed May 3, 1913. Serial No. 765,241.

To all whom it may concern:

Be it known that I, SVANTE R. W. M. BAGER, a subject of the King of Sweden, residing at Milwaukee, in the county of Milwaukee and State of Wisconsin, have invented a certain new and useful Improvement in Drag-Line Excavators, of which the following is a specification.

My invention relates to improvements in drag line excavators and the like and is illustrated diagrammatically in one form in the accompanying drawing, wherein—

Figure 1 shows the bucket in the excavating position; Fig. 2 shows the bucket in the carrying position; Fig. 3 shows the bucket in the dumping position.

Like parts are indicated by like letters throughout the several figures.

The bucket A open at front and top is provided with the excavating lip A¹. The sides are cut away upwardly and forwardly from the excavating lip A¹ and terminate in the fingers or lugs A² having a cross bar or stud member A³ connecting them. A hoisting bail or yoke A⁴ is pivotally mounted on the bucket A at a point back of the center of gravity. A stop A⁵ on the sides of the bucket in opposition to the yoke or bail A⁴ limits its forward movement toward the nose 30 of the bucket. The hoisting bail or yoke A⁴ carries the sheaves A⁶ A⁷ thereon. A drag line A⁸ leads from a hoisting engine not shown to the nose of the bucket.

A boom B is supported on the platform or frame or derrick not shown and carries the sheaves B¹ B² thereon. A brake B³ on the boom B is adapted to be operated by a connection B⁴ from any suitable mechanism not shown to control or arrest at the will of the operator the movement of the sheave B¹. A hoisting line B⁵ leads from a hoisting engine not shown along the sheave B¹ depending downwardly to form a loop B⁶ about the sheave A⁶ passes up over the sheave B¹ and downwardly in a free end over the sheave A⁶ to a point of attachment B⁷ on the cross bar A³ at the nose of the bucket. The hoisting line thus terminates in a downwardly depending loop and end both of which are 45 in movable connection with the bail or yoke, the end being also in fixed connection with the nose of the bucket.

It will be evident that, while I have shown in my drawing an operative device, still many changes might be made in size, shape

and arrangement of parts without departing materially from the spirit of my invention, and I wish, therefore, that my drawing be regarded as in a sense diagrammatic.

The use and operation of my invention are as follows:—With the bucket in the digging position as shown in Fig. 1, when the drag line is drawn in the bucket will be dragged forward and, since the drag line is attached to the bucket at a point forward of and above the cutting edge or lip, the bucket will tilt forwardly and downwardly to dig as indicated. When the bucket has been filled the drag line will be loosened and the bucket will then settle down into a horizontal position. The hoisting line will then be drawn in. The tension in the line will, since it is applied directly to the bucket at the nose, tend to tip the nose upwardly and rearwardly toward the yoke and rotate the bucket into the position shown in Fig. 2 until the yoke comes in contact with the stop on the bucket when further rotation will cease and the bucket will be raised. The fact that the yoke is pivoted to the bucket at a point behind or below the center of gravity would tend to make the bucket tip downwardly but this tipping movement is overcome by the pull of the hoisting line which tends to force the nose of the bucket to approach the sheave over which it passes on the yoke. Since the leverage through which this force acts is much greater than the leverage through which the mass of the bucket acts it will be evident that, while this force is equal to only one-third the weight of the bucket, still the bucket will be tipped into the carrying position as shown in Fig. 2 quite independent of the drag line and, as long as the tension in the three parts of the hoisting rope remains equal the bucket will swing in the carrying position and may be swung back and forth beneath the boom without disturbing its equilibrium. When it is desired to dump the bucket it is necessary only to apply the brake and hold the bucket end of the hoisting rope in the fixed position while continuing to raise on the loop and shorten it. This will raise the hoisting yoke and permit the sheave on the yoke to ride up along the bucket end of the hoisting rope, thus permitting the distance between the sheave and the nose of the bucket to increase. This will continue until the bucket dumps when the end of the rope becomes 110

slack. Owing to the shortening of the loop the bucket will swing over into the position shown in Fig. 3 being supported then only by the loop in the hoisting rope and the 5 sheave on the yoke over which it rides. The bucket will, of course, tend to tip upside down but this movement is limited by the contact of the rear end of the bucket with the bucket end of the hoisting rope. If the 10 bucket is then released and the hoisting rope slackened away the bucket will drop, nose first, into the ground to assume the digging position shown in Fig. 1 and the process may be repeated.

15 It will be observed that the bucket when in the dumping position tips so far that there will be no chance for any material to remain in the bucket and it will assume such a vertical position that it can be dropped, 20 nose first, as indicated. Experience shows that as the bucket is raised by the loop alone the rotational movement of the bucket becomes more and more rapid and the bucket finally swings around with a jerk jerking 25 the material out, this being particularly desirable when soft or sticky material is being excavated.

It will be noted that an essential requirement in the operation of my bucket is that 30 the bucket hoisting yoke be supported on the bucket at such a position that the center of gravity is always between the nose of the bucket and the pivotal point of the yoke and never behind it, for it is the weight of the 35 bucket applied at the center of gravity which tends to swing the bucket into the dumping position and this weight is always resisted until the dumping position is assumed by the bucket end of the cable connected 40 with the nose of the bucket and passing over the sheave on the yoke. The yoke I have shown rigid. It is quite obvious that it might under some circumstances be flexible or yielding and that the sheaves 45 might be differently positioned on the yoke. In any event the operation, however, would be exactly the same.

The three-part hoisting or lifting line may be thought of as provided with a connection which is pivotally attached at its 50 lower end to the bucket back of its center of gravity. This is the lifting point from which or by which the bucket is at all times during the lifting or dumping operation 55 lifted. At the same time the short or bucket end of the line may be thought of as a connection from the forward one of the three

parts of the lifting or hoisting line to the tilting point near the forward end of the bucket. In point of fact, of course, the three 60 parts of the hoisting lines are continuous throughout but functionally the bucket end of the hoisting line may like the yoke be thought of as a connection from one of the three parts of the lifting lines just as the 65 yoke may be thought of as a connection from the three parts of the lifting or hoisting line.

I have used the term, yoke, to describe the part indicated by the reference letters A⁴. 70 It may also be described as a bail. It may consist of any material, can be of any size or shape, the point being simply that it furnishes a connection between the bucket movably mounted thereon and the hoisting rope. 75 I have spoken of the two connections between the hoisting rope and the bail as made by means of pulleys, but of course any kind of arrangement whereby the rope may have motion along this portion of the bail 80 will be satisfactory. I wish it understood that I use the terms yoke or bail and the term pulleys with these meanings.

I claim:

1. In a drag line excavator, the combination of an excavating bucket with a hoisting line having a downwardly depending loop and a downwardly depending end, the latter being attached to the bucket adjacent the front thereof, a hoisting bail attached to the 90 bucket back of the center of gravity thereof and having a movable connection both with the downwardly depending loop and with the free end of the line, and a drag line attached to the bucket. 95

2. In a drag line excavator, the combination of an excavating bucket with a hoisting line having a downwardly depending loop and a downwardly depending end, the latter being attached to the bucket adjacent the front thereof, a hoisting bail attached to the 100 bucket back of the center of gravity thereof and having two pulleys, one engaging the loop and the other that portion of the line having the free end and a drag line attached 105 to the bucket.

In testimony whereof, I affix my signature in the presence of two witnesses this 13th day of April 1913.

SVANTE ROBERT WILLIAM MATTESON BAGER.
